UNITED STATES PATENT OFFICE

EDWARD B. MANLEY, OF NEW YORK, N. Y.

SAFETY RAZOR HEAD AND BLADE

Application filed January 9, 1931. Serial No. 507,730.

This invention relates to razors and particularly to an improved safety shaving head, the object being to provide an improved construction which is simple, strong and very convenient, and which presents a combined blade and holder forming what may be termed a one-piece unit.

Another object of the invention is to provide a shaving head unit wherein there is presented a one-piece unit adapted to be connected and disconnected with a handle at any time, while the shaving head unit presents a blade with cutting edges, holding means and a guard structure permanently associated together and, in effect, presenting a one-piece structure.

A further object of the invention, more specifically, is to provide what may be termed a one-piece unit shaving head consisting of a guard plate, a blade and a supporting or backing plate rigidly and permanently secured by riveting, welding or other means together and forming a single unit.

An additional object is to provide a unit shaving head which may include only a guard plate and blade arranged to present substantially a single piece structure capable of being connected to a handle and disconnected therefrom at will.

30 In the accompanying drawing—

Figure 1 is a bottom plan view of a shaving head unit disclosing an embodiment of the invention;

Figure 2 is a sectional view through Figure 1 approximately on the line 2—2, the same being shown in connection with a handle illustrated in elevation, except that part near the shaving head unit;

Figure 3 is a perspective view showing the various parts of the shaving head unit separated;

Figure 4 is a view similar to the upper part of Figure 2, but showing a modified construction;

Figure 5 is a view similar to Figure 4 but showing a second modified construction;

Figure 6 is a view similar to Figure 5 but showing a modified structure wherein a guard plate and a blade are used as a single unit;

50 Figure 7 is a view similar to Figure 6 but

showing a further modified form of the invention;

Figure 8 is a modified form of the invention illustrated in Figure 7.

Referring to the accompanying drawing by numerals, 1 indicates a handle of any desired kind, and 2 a shaving head unit. It will be understood that the shaving head unit presents the inventive idea but must be used with some form of handle, the handle 1 shown in Figure 2 being of the desired kind having a threaded bore 3 for receiving a threaded shank 4, which has a head 5 riveted or otherwise rigidly secured to the holding plate 6 of the shaving head unit.

The holding plate 6 is made arc-shaped, as shown in Figure 3, while the blade 7 is preferably a thin flexible blade normally flat and straight with two cutting edges. This blade is shown as riveted between the holding plate 6 and the guard plate 8, but it is to be understood that it may be secured rigidly in place by other means as for instance, welding, screws or the like.

When the parts are assembled and clamped firmly together suitable means, such as rivets 9, welding or other fastening means, are used to grip the parts permanently together as above specified. The guard plate 8 is provided with any desired form of guard fingers 10 and 11 which guard the respective edges 12 and 13 of the blade 7. The threaded stud 4 is shown of some appreciable length in the drawing, but it is understood that the same may be made any desired length according to the shape of the threaded bore of the handle, and this stud together with plates 6 and 8 and the blade 7 when rigidly and permanently connected together form the shaving head unit. When the parts are arranged as shown in Figure 2 the device is ready for use.

In many forms of double-edged safety razors now in common use there is provided a handle and a plurality of other members including a head or holder which receives the blade whereby when one blade becomes dull the same may be removed and a new one substituted. This structure is such that all the parts must be cleaned thoroughly in order to keep the razor in proper shape, and

there is besides danger of injury to the person handling the blades.

Also the various parts used in clamping the blades in place are more or less difficult 5 to clean and dry, so that to keep the safety razor of the type now in common use in good shape requires considerable attention. In the present instance there is no holder in the same sense as is true of the safety razor now 10 in common use, but only a unit which has been termed a shaving head unit, which is connected directly to a suitable handle by threads as shown in Fig. 2 of the accompanying drawing. It will, therefore, be evident 15 that the blade 7 with the respective plates 6 and 8 and the stud 4 form the shaving head, and that this head is applied or removed as a unit, the remaining part of the razor consisting of the handle 1. As the 20 parts are all permanently and rigidly secured together it is only necessary to clean the shaving head unit in hot water after each shaving operation, and the parts will be thoroughly cleaned and ready for use at another time. When both edges 12 and 13 of 25 blade 7 have become dull the complete shaving head unit is removed from the handle and thrown away without danger from cutting and a new complete shaving head unit substituted, whereupon the device is again in condition for use.

The plates 6 and 8 are preferably very thin but they must be sufficiently strong to present a comparatively stiff structure which will 30 hold the blade firmly positioned, as shown in Figure 2. Preferably the guard plate, as well as the holding plate, is stiffened by the use of embossed or pressed out reinforcing or stiffening beads 30.

40 In the drawing no stiffening beads show on the holding plate, but it is evident that the same can be formed on the holding plate in the same manner as illustrated with respect to the guard plate.

45 Figure 2 shows a desired form of safety razor but it will be evident that many modified forms showing the same inventive idea might be used without departing from the spirit of the invention.

50 In Figures 4 and 5 two modified forms showing the same inventive idea have been disclosed illustrating clearly that the same inventive idea may be used readily with a large number of slightly different structural arrangements. In Figure 4 there is provided a holding plate 3' and a guard plate 8'. A stud 4' is secured to the plate 3' by welding, riveting or any other desired means. In this form of the invention the holding plate 3' 55 is provided with depressions or recesses 14 and 15 while the guard plate 8' is provided with offset portions 16 and 17 whereby sockets are presented for receiving the respective blades 18 and 19. These blades are very thin 60 blades similar to blade 7 but provided with

only one cutting edge and made much narrower. The respective rivets 20 and 21 extend through the respective blades 18 and 19 and through the plates 3' and 8' whereby these plates are rigidly and permanently secured together and also the respective blades are rigidly and permanently mounted in position.

70 The complete shaving head unit, as shown in Fig. 4, is designed to be applied to and be removed from a handle in a similar manner to handle 1, and when the edges of the blades 18 and 19 become dull the entire head is thrown away.

75 In Figure 5 the blades 3' and 8' are combined in one plate, namely, the supporting plate 22 which is bent back upon itself at points 23 and 24, and then bent again upon itself at points 25 and 26 for forming sockets 80 for receiving the respective blades 18' and 19'. Rivets 20' and 21' extend through the various parts as shown in Figure 3 for rigidly clamping the respective blades to the supporting plate 22. The respective sections 27 and 28 merge into the guard fingers of the 90 type shown in Figures 2 and 3, or any other desired form of structure. In this form of the invention the supporting plate 22 is provided with pressed-up beads 29 for reinforcing and stiffening the plate. In Figure 1 the 95 clamping plate 6 is provided with a number of pressed-up reinforcing and stiffening beads 30. These stiffening portions are not shown in Figure 4, but they can be used there, if desired. Also, if desired, they can be 100 eliminated but where eliminated the clamping plate would usually be slightly thicker to secure the desired stiffness. It will therefore be noted that the guard is provided with 105 ribs which project toward the blade engaging surface and terminates in the teeth or fingers of the guard.

110 In Figure 7 a further form of the invention is shown which is similar to Figure 6 except that there is no central aperture in the blade 7', and in reference to the guard plate 8' it will be seen that the same is provided with a pressed out tubular member 31 which is threaded internally, although it could be 115 threaded externally. This arrangement permits a handle having a threaded extension to be used, but if a handle similar to handle 1 in Fig. 1, is used the threads could be arranged externally.

120 In Figure 8 a further modified form is shown wherein an interiorly threaded eyelet 32 is provided instead of the stem 4. This is adapted to receive a handle having a threaded end which may be screwed directly into the eyelet or screwed into the integral extension 31 of the structure shown in Figure 7. In this form of the invention as well as in the form shown in Figure 1 the blade is 125 protected at all times whereby danger of accidental cutting during the handling of the 130

blade is practically eliminated, so that the blade may be easily applied or discarded safely. The blade and the respective plates coacting therewith are very thin and consequently rivets have been used to rigidly clamp the parts permanently together. By reason of the thinness of the respective parts, threads could not be provided in either of the plates and consequently a clamping screw could not be used nor would it be feasible to use bolts as the same presents objectionable projections. It is, therefore, to be understood that rivets, welding or other means might be used which do not present projections and which would cooperate with thin plates.

What I claim is—

1. In a shaving head unit a pair of thin holding plates one of said plates having fingers acting as a guard, a threaded stud permanently connected with and extending from one of said plates functioning to receive a handle when the unit is in use, a cutting blade positioned between said plates provided with cutting edges on the opposite sides, and rivets for rigidly and permanently non-removably securing said blade to said plates.

2. In a shaving head unit a pair of thin arc-shaped holding plates, a threaded stud permanently secured to and extending from one of said plates and permanently extending through the other plate, said stud being adapted to receive a handle when the unit is in use, a cutting blade permanently arranged between said plates and provided with cutting edges on opposite sides, and rivets extending through said plates and blade for rigidly and permanently securing said blade to said plates.

3. In a shaving head unit a blade having a cutting edge, a supporting plate for said blade, said plate being comparatively thin and incapable of receiving threads, rivets for permanently and rigidly securing said blade to said plate, means mounted upon said head presenting a threaded stud adapted to receive a handle when the unit is in use said stud upstanding from a central position on said plate, and means extending from said plate presenting guards.

4. In a shaving head unit, a blade having a pair of cutting edges, supporting plates for said blade, rivets for permanently and rigidly securing said blade to said plates, means mounted upon said unit presenting a threaded stud whereby the unit may be connected with a handle when in use, and means forming ribbed guards extending from each edge of one of said plates.

5. In a shaving head unit a substantially wafer plate formed with guard fingers, a wafer blade carried by said plate, rivets for connecting said blade permanently to said plate and a threaded stud extending from

said plate through said blade and permanently and rigidly connected to said plate.

6. In a shaving head unit a guard plate provided with guard fingers on opposite edges, and a centrally positioned aperture, a normally flat blade having cutting edges on opposite sides coacting with said fingers, said blade having a centrally positioned aperture, a holding plate formed with an aperture, and a stud rigidly secured to said holding plate, said stud extending through said aperture in said blade and in said guard plate and formed with threads for receiving a handle whereby the handle may be removably connected with the unit, and rivets for rigidly and permanently securing said guard plate and holding plate and said blade together.

7. A shaving head unit including a holding plate, a guard plate, a stud secured to said holding plate and extending through said guard plate, said stud being positioned centrally of said plate and extending normally to the surface thereof, said guard plate being provided with a pair of offset portions extending from the respective edges inwardly, a pair of flat blades having cutting edges, one blade being fitted into each of said offset portions so that the cutting edges thereof will project beyond the offset, and rivets for each blade extending through the respective plates and also through the respective blades for permanently and rigidly securing the blades and plates together.

8. In a shaving head unit a plate provided with a threaded handle receiving stud positioned centrally of and extending normally to the surface of said plate; said plate being at each edge portion bent back on itself to present sockets, a portion of each edge having guard fingers, a blade fitted into each socket, and rivets for each blade for permanently and rigidly securing the blades in position.

9. In a shaving head unit a double edged blade, a guard plate fitting against said blade formed with guard fingers extending beyond the edges of the blade, means for rigidly and permanently securing the guard plate and blade together, said plate at the center being formed with an integral pressed out hollow boss internally threaded for receiving a handle.

10. In a shaving head unit a double edged blade, said edges being parallel, a guard plate fitting against said blade, said guard plate having guard fingers extending beyond the edges of said blade, means for permanently and rigidly securing said blade and plate together, said blade and plate having centrally positioned apertures, and an internally threaded eyelet firmly fitted in said aperture, said eyelet being adapted to receive the threaded end of a handle when the unit is in use.

11. A shaving head including a plate hav-

- ing a handle receiving portion, a blade mounted on said plate, a guard plate provided with guard fingers, said guard plate being also provided with ribs which project 5 toward the blade engaging surface of the guard plate and terminating in the fingers of the guard plate and rivets for rigidly and permanently securing said plates and blade together.
- 10 12. A shaving head unit including a blade having a cutting edge, substantially wafer top and bottom plates fitted against said blade, rivets extending through said top and bottom plates and said blade for permanently 15 securing said blade and plates together and a threaded stud upstanding from the center of one of said plates and extending through the other plate and blade for connecting the shaving head unit to the handle.
- 20 13. In a safety razor, a removable handle and a shaving head unit, said shaving head unit comprising a pair of holding plates, a blade arranged therebetween, one of said plates being of substantially less width than 25 said blade and the other of said plates being of greater width than said blade and formed with guarding fingers adjacent the edges of said blade, rivets for permanently and rigidly securing said plates and blade together, said 30 rivets extending through said plates and blade and an upstanding threaded stud carried by one of said plates substantially centrally thereof, said stud being adapted to receive said removable handle.
